UNITED STATES PATENT OFFICE.

HARRY C. FOSTER, OF CONNERSVILLE, INDIANA, ASSIGNOR, BY DIRECT AND MESNE ASSIGNMENTS, OF ONE-HALF TO INDIANA LAMP CORPORATION, OF CONNERSVILLE, INDIANA, A CORPORATION OF DELAWARE, AND ONE-HALF TO GENERAL MOTORS CORPORATION, OF DETROIT, MICHIGAN, A CORPORATION OF DELAWARE.

LAMP CONSTRUCTION.

Application filed January 29, 1925. Serial No. 5,530.

This invention relates to lamp construction and is herein illustrated as embodied in automobile headlights.

One of the objects of this invention is to provide simple and efficient focusing mechanism for a lamp bulb, capable of being easily assembled in its casing where it is positioned by the reflector. Another object is to provide a flexible or floating focusing device for longitudinally adjusting a lamp bulb without any tendency to move the bulb laterally of the reflector axis or to distort the reflector. Still another object is to provide an improved lamp door attaching means to avoid the usual, expensive hinged door and the disadvantages of rotary doors which become difficult to remove on account of corrosion and otherwise are a source of complaint.

20 To these ends and also to improve generally upon devices of the character indicated my invention consists in the various matters hereinafter described and claimed.

In the drawings, Figure 1 is a front view 25 of a headlight, partly broken away and in section.

Figure 2 is a vertical central section.

Figure 3 is a detail of the lamp socket.

30 Figure 4 is a vertical section on the line 4-4 of Figure 2.

Figure 5 is a sectional view of details on the line 5-5 in Figure 1.

Figure 6 is a horizontal section of the lamp socket.

35 Figure 7 is a vertical section of a modification.

Figure 8 is vertical section of another modification on line 8-8 of Figure 9.

Figure 9 is a section on line 9-9 of Figure 40 8.

Figure 10 is a vertical section of a modification.

Figure 11 is a vertical section of another modification.

Figure 12 is a view partly in plan and partly in section of the central part of the reflector.

Figure 13 is a vertical section of a modification.

50 Figure 14 is a perspective view of a detail.

In the drawings, the numeral 10 indicates a reflector carrying a rearwardly extending sleeve or guide 12 for a slidable lamp socket

14. The socket 14 has a bayonet slot 16 to receive the usual pin carried by a lamp bulb 18. The sleeve 12 is slit longitudinally at 20, preferably at the top, to embrace the sides of a downturned arm 22 on the base of a U-shaped plate 24 the other arm 26 of the plate being parallel to arm 22 and threaded to receive an adjusting screw 28. The screw 28 passes loosely through the back wall 30 of a lamp casing 32 and a coil spring 34 surrounds the screw between the casing and the arm 26.

65 The socket 14 has an oblong opening at the top formed by a slot 36 and end extensions 38 adapted to allow entrance of a cross lug 40 formed at the lower end of the arm 22. The slot registers with the cross lug 40 only when the socket 14 is turned at right angles to the position shown and, after the socket is turned to its normal position, the cross lug holds the socket against rotation on its axis and controls 70 its longitudinal position in the sleeve 12. A coil spring 42 surrounds the arm 22 bearing against the base of the U-shaped plate 24 and against a concave plate 44 fitting 75 the sleeve 12. The plate 44 is slotted similarly to socket 14 to allow passage of the cross lug 36. The plate 24 has short extensions 46, at the base of the arm 22, forming abutments for the spring 42.

80 The U-shaped plate 24 with its screw 28, spring 34, plate 44, and spring 42 is first attached to the rear wall 30 of the casing. Then, the socket 14, without its lamp bulb 18, is turned at right angles to the position shown in Figure 2 and its slot 36 passed up over the cross lug 40. Then the socket is turned back to its normal position where it will be flexibly or yieldingly held. It can be tilted, however, in any direction relatively to the adjusting mechanism to receive the reflector. The reflector 10 is next attached to the casing, its sleeve 12 sliding over the socket 14 to center the latter. During this operation, the concave plate 44 is lifted a little so that the slit at 20 can embrace and slide along the sides of arm 22. Finally the lamp bulb 18 is inserted in the socket.

100 Insulated wires 50 are passed through the back wall of socket 14 and through an insulating disc or contact carrier 52 where tacks 105 54 are driven into the ends of the wires

between the strands thereof to form contact points to engage the usual contacts on the rear of the lamp bulb 18. A coil spring 56 surrounds each wire and is interposed 5 between the back of the socket and a disc 58 which bears against and moves with the disc 52. The disc 58 has lugs 60 entering slots 62 in the socket to hold the contact points in line with the lamp contact points 10 which are positioned by the usual pins entering bayonet slots. This construction allows the contact carrier or disc 52 to have a wobble motion, insuring electrical contact at two points, and the two individual coil 15 springs 56 leave room at the top of the socket for the cross lug 40 above mentioned.

The reflector 10 has a circular channel for the usual packing or cord 64 against which the glass or lens 66 is held by a glass holding 20 or door casing in the form of a ring 68. The ring has suitably spaced clips 70 (Figure 1) with projections 72 entering positioning slots in the edge of the glass. The door casing has an outer peripheral flange 74 to enclose 25 the end of the lamp casing 32 and it is held to the lamp casing under spring pressure by the construction to be described.

At the top of the door casing, is secured a bracket plate 76 having two spaced inwardly 30 extending lugs 78. At the rim of the lamp casing is an inwardly extending flange 80 abutting against an outwardly extending flange 82 on the reflector. Fixed at the top 35 of the lamp casing, inside the flange 80, is a bracket plate 84 which extends forwardly through a notch in the casing flange 80 and through a cut away portion of the reflector flange 82. This extended portion of the plate 84 is flat with a substantially rectangular opening at one end of which is a lug 86 entering one end of a coil spring 88. The other end of the spring bears against the depressed central portion of a channel plate 90 which has a central slot for the passage 45 of plate 84. The channel plate is arched or bowed so that its ends are offset forwardly from the body and the lugs 78 on the door casing straddle the plate 84 and engage behind the offset ends of the channel plate. 50

The door casing is first attached at the top and then swung down and fastened at the bottom. The lugs 78 are first brought down in the space behind the offset ends of the channel plate. Then with the upper portion of the cord 64 as a fulcrum, the glass and door casing are swung downwardly at the bottom, thereby compressing the spring 88 and keeping a tension on the door casing to prevent rattle. The lower end of 55 the door also has a spring fastening to be described. It should be noted that the upper spring fastening is so constructed that the reflector flange 82 will be yieldingly held against the flange 80 of the lamp casing before the door casing is applied.

The lower fastening may be constructed as shown in Figures 2, 10 or 11 depending on the type of lamp. In Figure 2, a two-armed anchor plate 92 has the end of its longer arm resting in the angle formed by the flange 80 70 and the lamp casing. The other arm slidably receives a bent rod 94 which passes through the casing and has a washer 96 and cotter pin at the end to form an abutment for a coil spring 98 surrounding the rod. 75 The spring bears against the anchor plate and furnishes the tension desired for holding the lower end of the door casing. The rod 94 has hooks 100 to engage openings in the door casing and terminates in a finger 80 piece 102 by which it may be manipulated. This construction provides a quick-detachable door which avoids the usual disadvantages of a hinged door or of a door that is attached to the rim of the lamp casing by a 85 rotary movement.

In Figure 7, the rim of the lamp casing has a slot 104 at the top for a substantially U-shaped spring 106, this spring being 90 engaged by a bead 108 on the rim of the door casing. The forward arm of the spring is received in a slot 110 at the rim of the reflector.

In Figures 8 and 9, the lamp casing 112 has an opening 114 at the rear side of which is a projection 116 slidably supporting a plate 118. The plate is held from turning by the projection and is pressed rearwardly by a coil spring 120 surrounding the projection 116 and a lug 122 on the lamp casing. 95 Fixed to the door casing 124 is a bracket 126 having a pair of spaced lugs or fingers 128 arranged to straddle the projection 116 and engage behind the plate 118. The operation 100 is similar to the construction first described. 105

In Figure 10, the lamp casing 130 has an extruded portion 132 apertured for the passage of a slidable rod 134. The rod carries a washer 136 at one end held by a cotter pin and a concave washer 138 surrounds the rod and bears against the extruded portion 132. The washers form abutments for a spring 140 coiled about the rod. The lower end of the rod 134 is bent around the rim of the door casing 142 where it is provided with one or more hooks 144 and a finger piece 146. In this figure, the glass 148 is supported independently of the door casing on substantially U-shaped springs 150 held in 110 registering slots cut in the flanges of the lamp casing 130 and the reflector 152. Each spring also engages a slot in the edge of the glass and its end is bent inwardly at 154 to hold the glass against the cord. 115 120

In Figure 11, the lamp casing 156 has a slot 158 for the passage of a slidable rod 160. The casing, at the forward end of the slot, fits between two fingers 162 and 164 formed by splitting the longer arm 166 of an angled anchor plate. The shorter arm 125 130

168 of the anchor plate slidably supports the rod and forms an abutment for one end of a spring 170 coiled around the rod and abutting against a hook 172 at the upper 5 end of the rod. The lower end of the rod is bent around the rim of the door casing 174 and has the hook 176 and finger piece 178 arranged as before. The reflector 180 is pressed rearwardly against suitable stops 10 (not shown) on the lamp casing and carries glass holding clips 182 which are passed through slits in the reflector and bent over its rim.

In Figures 13 and 14, there is illustrated 15 a desirable construction for securing the top of the door casing. The forward edge of the lamp casing 184 slidably supports a substantially U-shaped plate comprising firstly, a base portion 186 passing through a 20 slot 188 in the lamp casing, secondly, a short arm 190 resting outside the casing, and thirdly, a longer arm 192 which passes through an inwardly extending flange 194 on the lamp casing. The longer arm 192 25 also passes through an outwardly extending flange 196 on the reflector and may be twisted or warped a little at its forward end to retain the flange. The slidable plate is cut out at 198 to receive a coil spring 30 200 which bears against the base portion 186 and against the inner side of the flange 194. The spring is held in the opening 198 by a lug 202 on the plate and normally tends to press the plate rearwardly. The plate 35 may have extensions 204 at each side of its base portion. A door casing or glass holding casing 206 surrounds the rim of the lamp casing and carries a right angular plate one arm 208 of which is secured to 40 the door casing and the other arm 210 of which extends inwardly through the slot 188 and engages behind the base portion 186 or its extensions 204.

Thus the door casing is yieldingly pressed 45 rearwardly to hold the glass against the reflector and to hold the reflector yieldingly against the lamp casing. The tension is produced, in a manner similar to that previously described, by drawing the lower 50 end of the door casing down and detachably securing it against the lamp casing.

Although the invention has been described by reference to certain specific constructions, it should be understood that, in 55 its broader aspects, it is not necessarily limited to the forms selected for mere illustrative purposes.

I claim:

1. In a device of the character described, a wall member, a reflecting surface, lamp 60 adjusting mechanism connected to the wall member and comprising a headed member, a lamp socket having a slot to allow the passage of the headed member in one position of the socket and to interlock with the headed member in another position of the socket, and means for slidably supporting the socket.

2. In a device of the character described, 70 a reflector having a guide extending rearwardly therefrom, a lamp socket slidable in the guide and having a slot, a lamp casing, adjustable mechanism connected to the casing and comprising an arm having a cross lug for detachable connection with the slot in the socket so that the lug is locked in the slot in one position and removable from the slot in another position at an angle to the first named position, and said 75 guide being slit longitudinally to allow the reflector to be slid over the socket after the adjusting mechanism has been attached to the latter.

3. In a device of the character described, 80 a reflector having a guide extending rearwardly therefrom, a lamp socket slidable in the guide and having a slot, a lamp casing, adjusting mechanism connected to the casing and comprising an arm having a cross lug for detachable connection with the slot 90 in the socket, and a spring pressed plate carried by the arm for pressing the socket towards said lug.

4. In a device of the character described, 95 a lamp casing, a reflecting surface within said lamp casing, a lamp socket having a slot, adjusting mechanism connected to the casing and comprising an arm having a cross lug for detachable connection with the slot in the lamp socket, a concave plate on the arm, and a spring for pressing said plate towards the socket and the socket 100 against the lug.

5. In a device of the character described, 105 a lamp casing, a reflecting surface within said lamp casing, a lamp socket, adjusting mechanism connected to the casing, and means for detachably connecting the adjusting mechanism to the socket, said last connection yieldably holding the socket in 110 its normal position and releasing the socket when the latter is turned at an angle.

In testimony whereof I affix my signature.
HARRY C. FOSTER.
